UNITED STATES PATENT OFFICE.

SAMUEL G. RHODES, OF NEW YORK, N. Y., ASSIGNOR TO THOMAS E. MURRAY, OF NEW YORK, N. Y.

ELECTROMAGNET.

1,183,237.

Specification of Letters Patent. Patented May 16, 1916.

Application filed February 5, 1916. Serial No. 76,307.

To all whom it may concern:

Be it known that I, SAMUEL G. RHODES, a citizen of the United States, residing at New York, in the county of New York and 5 State of New York, have invented a certain new and useful Improvement in Electromagnets, of which the following is a specification.

The invention is an electro-magnet so 10 constructed that when controlled by a current in one direction, the armature is moved to a certain position and there held—when controlled by a current in the other direction, the armature is moved to a certain 15 other position and there held, and when the controlling current is interrupted, the armature remains in whichever position it may stand at the time of the interruption.

In the accompanying drawings—Figure 1 20 is an elevation of my electro-magnet, the left hand half being in section. Figs. 2 and 3 are diagrams illustrating the relations of the coils and armature, the armature being shown in two different positions. Fig. 4 is 25 an electrical diagram showing my electro-magnet disposed in a three-wire system and as part of an apparatus for opening and closing a lamp circuit from a distant station.

30 Similar numbers and letters of reference indicate like parts.

The electro-magnet has three coils A, B and C. The two coils A, B are connected in series and are alike except that they are 35 wound in opposite directions. The coil C is here wound outside of the coils A and B. The relation of the coil C to the coils A, B is to be such that one half of coil C in ampere turns equals coil A, and the other half 40 equals coil B. But since the coils A, B are wound in reverse directions, the magnetizing effect of the current in one coil, as A, will be supplemented by that of the current which is moving in similar direction in coil C, while 45 the magnetizing effect of the current in the other coil wound in the opposite direction, as B, will be counterbalanced by the current in coil C. Hence the armature D of the magnet will be moved in one direction or the 50 other, depending upon the direction of the current in coil C, and will remain in the position into which it is moved until the current is reversed in coil C. Thus, referring to Figs. 2 and 3, the coil C is divided into 55 halves above and below the broken line 1, 2.

The half 3 which is above line 1, 2 is equal in ampere turns to coil A, and the half 4 which is below line 1, 2 is equal in ampere turns to coil B. The coils A and B being equal to one another will counterbalance one another, as indicated by the arrows 5, 6. If the current in coil C, as shown in Fig. 2, be in the direction of arrow 7, then obviously the half 3 of coil C will supplement coil A, while the half 4 of coil C will counterbalance coil B, and the armature will rise to the position indicated in Fig. 2. If, on the other hand, the current in coil C be reversed, as shown in Fig. 3, and hence in the direction of arrow 8, then the half 4 of coil 70 C will supplement coil B, while the half 3 of coil C will counterbalance coil A, and the armature will descend to the position indicated in Fig. 3. Hence by alternately reversing the current in coil C, the armature 75 D may be moved from one position to the other, and when the current is interrupted to coil C, the armature will remain in the position last taken.

This electro-magnet may be applied to a 80 great variety of uses—as, for example, in telegraphy for the operation of relays, or for controlling light or power circuits from a distance. In Fig. 4 I have illustrated one 85 practical application of it to an apparatus for the control from a distance of a circuit including an electric lamp. I have described and claimed said apparatus in another application for Letters Patent, Serial No. 76,306, filed simultaneously herewith, and 90 therefore do not claim said apparatus herein.

Referring to Fig. 4: E and G represent the plus and minus potential mains of a 95 three-wire electric light system, F being the neutral main. Said mains are connected to the generators H, I in the usual way. J is an arc lamp connected to the positive main E and the neutral main F. The light circuit contains a switch K which is to be 100 opened and closed to break or make said circuit, and so to extinguish or establish the light at the will of an operator at a distant station X, through the agency of a single 105 conducting wire L leading from said distant station to the place where the lamp is situated. At said distant station X, wire L is connected to the pivot of a bell crank switch lever M, which lever may be moved into contact with the terminal of a lead N 110

from the positive main E or the terminal of a lead O from the negative main G. The switch K is carried by the armature D of the electro-magnet. By moving the switch M at the distant station to make circuit with lead N or O, the current to coil C is alternately reversed; hence switch K is caused to open or close the circuit to lamp J, and after the current is interrupted at switch M, 10 said switch K will remain in its last position.

I claim:

1. An electro-magnet, having three coils, two of said coils being wound in relatively opposite directions and connected in series 15 and each having the same number of ampere turns, and the said third coil having ampere

turns equal in number to the sum of the ampere turns of said two coils.

2. An electro-magnet, having three coils, two of said coils being wound in relatively 20 opposite directions and connected in series and each having the same number of ampere turns, and the said third coil inclosing said two coils and having ampere turns equal in number to the sum of the ampere turns of 25 said two coils.

In testimony whereof I have affixed my signature in presence of two witnesses.

SAMUEL G. RHODES.

Witnesses:

GERTRUDE T. PORTER,
MAY G. McGARRY.
